SWIMMING DEVICE

George Komadina, Gallup, N. Mex., assignor of
one-third to Tony Yurcic and one-third to Pete
Mervosh, both of Gallup, N. Mex.

Application April 10, 1934, Serial No. 719,960

2 Claims. (Cl. 9—21)

This invention relates to a swimming device especially adapted for aiding a person in swimming or learning to swim and has for the primary object the provision of hand and feet devices similarly constructed which will provide maximum traction for the feet and hands in the water to materially aid to maintain the person at the surface of the water and permit the person to progress through the water at a maximum rate of speed.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a view illustrating a person in swimming position with swimming devices applied to the feet and hands and constructed in accordance with my invention.

Figure 2 is a top plan view illustrating one of these devices or the device adapted for use on the hand.

Figure 3 is a sectional view taken on the line 3—3 of Figure 2.

Figure 4 is a sectional view taken on the line 4—4 of Figure 2.

Figure 5 is a top plan view illustrating the device adaptable for use on the foot.

Figure 6 is a bottom plan view illustrating the same.

Figure 7 is a sectional view taken on the line 5—7 of Figure 5.

Figure 8 is a sectional view taken on the line 8—8 of Figure 7.

Figure 9 is a view illustrating a person maintained partially above the surface of the water by the use of my invention on the hands thereof.

Referring in detail to the drawings, the characters 1 and 2 indicate hand and feet devices each including a main plate 3 having hinged thereto blades 4. The main plate of the hand device 1 is substantially egg-shaped in outline provided adjacent opposite ends thereof with openings 5, one of which has mounted to the walls thereof a cushion element 6 to provide a rest for one of the fingers of the hand while the other opening may be employed for suspending the device on a hook or like support. Secured substantially centrally of and to the under face of the main plate is a hinged plate 7 provided with pairs of spaced pintle barrels 8. The barrels 8 of each pair support a pintle 9. The

blades 4 are partially overlapped by the main plate and the opposing edges thereof are extended and shaped to form pintle barrels 10 journaled on the pintles 9 whereby the blades may pivot relative to the main plate and move in one direction within the water. The blades 4 each are of substantially semi-circular shape and the edges thereof are reinforced by a beading 11. The barrels 10 are of substantially triangular shape in cross section which will permit the blades to hinge relative to the main plate and provide stops for limiting the movement of the blades towards each other by abutting the hinge plate 7, as shown in Figure 3. The outer edges of the blades are not provided with the beads 11 and are slightly curved, as shown at 12. These slightly curved and substantially sharp outer edges 12 allow the blades to cut through the water with great efficiency while the beadings 11 reinforce and rib the active faces of the blades and likewise serve to hold the water engaged by the blades scooped in said blades and thus materially facilitate propulsion by the swimmer.

The main plate of the hand device is offset and slotted adjacent to opposite edges thereof, as shown at 13, providing mediums to receive or permit the connection of a hand strap 14 to the main plate. The swimmer's or person's hand is placed on the main plate with a finger engaging in the opening 5 and the hand strap passing over the hand, as shown in Figures 1 and 9. The hands of the person equipped with the devices 1 will permit the hands to obtain greater traction in the water while on a working stroke and when returning on a non-working stroke the blades 4 automatically swing to substantially right angles to the main plate, as shown in Figure 3, thereby reducing the resistance of the movement of the hands through the water on the non-working stroke or motion of the arms of the person.

The foot device 2 includes a main plate 15, the general outline thereof being substantially in conformity to the shape of a person's foot and has hinged thereto blades 16 similarly constructed and shaped to the blades 4. The hinge connections between the main plate 15 and blades 16 are in accordance with that described in reference to the hand device. The main plate 15 at opposite sides thereof adjacent the toe portion is provided with slotted ears 17 to receive straps 18 each including sections connected by a buckle 19. The straps 18 cross each other and are adapted to extend over the foot of a person between the toes and the instep. The heel portion of the main

plate 15 is equipped with slotted ears 20 to which is connected an ankle strap 19, the latter including sections connected by a buckle 20'. The ankle strap or the sections thereof cross each other as will be apparent in Figure 5 and is adapted to encircle the ankle of the person. The use of the foot device 2 upon the swimmer is in accordance with that heretofore described in connection with the hand devices and the main plate 15 has secured to its under face cushioned blocks 21 to form tread portions for the device when walking on the ground or beach. Elastic elements 22 are secured to the ears 17 and are adapted to be brought in engagement with hooks 23 secured to the blades 16 for maintaining the blades in a plane substantially with the plane of the main plate when the device is worn by a person when walking on the ground or the beach.

Devices applied to the feet and hands of a person, as shown in Figure 1 will materially aid the person in learning to swim or to increase the rate of speed at which the person may travel through the water. The use of the hand devices will permit a person to assume a position shown in Figure 9 wherein the major portion of the body and head are disposed above the surface of the water while the legs incline forwardly and upwardly to position the feet above the surface of the water. The hand devices when used in this manner will permit a person to remain afloat with comparative ease.

Having described the invention, I claim:

1. In a swimming device, a flat main plate to be attached to the hands or feet of the user and having adjacent its ends round openings, a hinged plate longitudinally arranged and centrally positioned on the main plate, flat semi-circular blades normally resting against the main plate and having substantially V-shaped barrels, pivots passing through the longitudinal edges of the hinged plate and said barrels, said blades having their edges from their straight inner edges to point equidistant from outer edges formed with a beading and the outer edge of said plates between such beading being slightly rounded in one direction. 15

2. In a swimming device, a flat main plate to be attached to the hands or feet of the user and having adjacent its ends round openings, a hinged plate longitudinally arranged and centrally positioned on the main plate, flat semi-circular blades 20 normally resting against the main plate and having substantially V-shaped barrels, pivots passing through the longitudinal edges of the hinged plate and said barrels, said blades having their edges from their straight inner edges to point 25 equidistant from outer edges formed with a beading and the outer edge of said plates between such beading being slightly rounded in one direction, and cushioning blocks fixed on the main plate, adjacent to the opposite ends of the hinged plate. 30

GEORGE KOMADINA.
